UNITED STATES PATENT OFFICE.

JOHN O. JOHNSON, OF CHICAGO, ILLINOIS.

COMBINATION-HANDSAW.

SPECIFICATION forming part of Letters Patent No. 514,080, dated February 6, 1894.

Application filed April 10, 1893. Serial No. 469,732. (No model.)

To all whom it may concern:

Be it known that I, JOHN O. JOHNSON, a subject of the King of Sweden and Norway, residing at Chicago, in the county of Cook and State of Illinois, have invented certain new and useful Improvements in Combination-Handsaws, of which the following is a specification.

This invention relates to improvements in hand-saws, having combined therewith certain devices for ascertaining the plumb and level of surfaces, and for describing thereon angles of various kinds; and consists in certain peculiarities of the construction, novel arrangement, and operation of the various parts thereof, as will be hereinafter more fully set forth and specifically claimed.

The objects of my invention are first, to provide a hand-saw of the ordinary construction, which shall have combined therewith an instrument or device for ascertaining the perpendicular position of walls or uprights, and the level of horizontal surfaces; and second, a saw which in addition to the above named device, shall have means for measuring and describing on surfaces various angles.

In order to enable others skilled in the art, to which my invention pertains to make and use the same, I will now proceed to describe it, referring to the accompanying drawings, in which—

Figure 1, is a view in side elevation of a saw in an inverted horizontal position, illustrating the position of the indicator, when the saw is in a level position. Fig. 2, is a similar view, partly in section, of a portion of the saw, showing it in an upright position, but out of plumb, and illustrating the position of the indicator, and the miter-piece in an extended position. Fig. 3, is a view partly in section of the miter-piece detached from the saw, and Fig. 4, is an edge view thereof.

Similar letters refer to like parts throughout the different views of the drawings.

A, represents the blade of a saw, which may be made of any suitable size, and material, and is provided on its cutting edge with ordinary saw-teeth a , and on its opposite edge, which is straight, with a scale or graduating marks a' , which may be placed on one or both sides of the surface of the blade, near or at its straight edge.

To one end of the blade A, is secured a hand-piece B, which may be made of the ordinary or preferred construction and form, and has a grip b , and an opening b' , through which the fingers of the hand are passed, and in which may operate the indicator C, which is pivotally secured to a portion of the piece B, as at c , and has its lower portion formed with an enlargement or weight c' , to cause it to depend.

As is clearly shown in Fig. 2, the lower portion, (when the saw is in position for use) of the hand-piece B, is provided with a recess b^2 , within which the indicator may rest or fit, and be retained by means of a suitable catch b^3 , when it is not in use.

As seen in Figs. 1, and 2, of the drawings, the upper portion of the opening b' , of the hand-piece B, is formed circular, and is provided with a scale or graduating marks d , which may be placed on one or both sides of the hand-piece, as is desired. To one side of the inner lower portion of the hand-piece B, or that part thereof which is secured to the blade or saw, is pivotally secured, as at e , a rod or piece E, which fits in a tube or sleeve D, which tube or sleeve is provided with a set-screw or pin d' , which passes through and operates in a longitudinal slot d^2 , formed in the blade, which slot extends from near the hand-piece B, longitudinally with the blade toward the free end thereof. The rod E, and sleeve or tube D, in conjunction, form an adjustable miter-piece, which is adapted to be used for describing different angles on a surface. When the miter-piece is not in use, it may be retracted to the position indicated in Fig. 1, when it and the straight edge of the blade, will form the right angle of a square, and in which position, it, the miter-piece may be firmly secured by means of the set-screw or pin d' , to the blade.

When it is desired to obtain a different angle from that attained when the miter-piece is in the position shown by continuous lines in Fig. 1, said piece may be moved to the position indicated by continuous lines in Fig. 2, or to any desired angle, as is obvious. It is apparent that by moving the miter-piece D, from the hand-piece B, the pin d' , will slide within the slide d^2 , and the rod E, which fits in the tube or sleeve D, will be partially with-

drawn therefrom, as indicated, thus extending the miter-piece to a suitable length.

The graduating marks or scale d , will enable the operator or user of the saw, to ascertain what degree the surface is out of plumb or level, for the indicator C, will always hang in a plumb or perpendicular position, and its point will indicate on the scale d , the degree thereof.

10 When it is desired to use the saw, as an ordinary one, the indicator or pointer C, may be folded into the recess b^2 , and there retained by means of the catch b^3 , which may be an ordinary button or other suitable device, and 15 the miter-piece D, may be secured to the position, indicated by continuous lines in Fig. 1, as before described.

It is apparent that I may use the miter-piece and omit the indicator, or I may sometimes employ the indicator and dispense with the miter-piece. It is also obvious that the scale a' , on the saw, affords a convenient measure or rule.

Having thus fully described my invention, 25 what I claim as new, and desire to secure by Letters Patent, is—

1. As an improved article of manufacture, a saw having a straight edge and an opening in its handle, provided with a graduated scale,

and an indicator pivotally secured to the handle and adapted to operate in its opening, substantially as described. 30

2. As an improved article of manufacture, a saw having a straight edge and an opening in its handle, said opening being provided 35 with a graduated scale, an indicator pivotally secured to the handle and adapted to operate in its opening, and an adjustable and extensible miter-piece pivotally secured to the handle, substantially as described.

3. The combination of the blade A, having the graduated scale a' , on its straight edge, the slot d^2 , with the hand-piece B, having the opening b' , the circular scale d , and recess b^2 , the indicator or pointer C, pivotally secured 45 to the hand-piece and adapted to operate in the opening b' , and to rest in the recess b^2 , the sleeve or tube D, having the set-screw or pin d' , to operate in the slot d^2 , and the rod E, pivotally secured to the hand-piece and 50 adapted to fit in the hollow of the tube D, all constructed, arranged and operating substantially as and for the purpose set forth.

JOHN O. JOHNSON.
